(Cl. D29—19)

To all whom it may concern:

Be it known that we, John F. Malley and Lucien Ribera, citizens of the United States, residing in Boston, Massachusetts, and New York city, New York, respectively, have invented a new, original, and ornamental Design for a Medal or Similar Article of Manufacture, of which the following is a specification, reference being had therein to the accompanying drawing, forming a part thereof.

In the drawings:

Fig. 1 is a top plan view of a medal embodying our design.

Fig. 2 is a transverse sectional view on the line 2—2 of Fig. 1.

The back of the article is flat and plain.

We claim:

The ornamental design for a medal or similar article of manufacture, as shown.

JOHN F. MALLEY.
LUCIEN RIBERA.
